SPACE ROCKET TOY

Andrew E. Jackson, Miami, Fla.

Application April 16, 1953, Serial No. 24,535

Term of patent 3½ years

(Cl. D34—15)

Fig. 1

Fig. 1 is a perspective view of a space rocket toy showing my new design in launching position.

Fig. 2 is a fragmentary bottom plan view of the rocket portion thereof; and

Fig. 3 is a fragmentary side elevational view thereof.

A portion of the launching stick in Figs. 2 and 3 and a portion of the launching platform in Fig. 3 have been omitted for convenience of illustration.

I claim:

The ornamental design for a space rocket toy, substantially as shown and described.
